(Cl. D85—2)

To all whom it may concern:

Be it known that we, Harry Pokras, a citizen of the United States, residing in Los Angeles, in the county of Los Angeles and State of California, and Harry R. Greene, a citizen of the United States, residing in Pasadena, in the county of Los Angeles and State of California, have invented a new, original, and ornamental Design for a Combined Registration Certificate, Cigarette and Match Holder, of which the following is a specification, reference being had to the accompanying drawing, forming a part thereof.

We claim:

The ornamental design for a combined registration certificate, cigarette and match holder, substantially as shown.

HARRY POKRAS.

HARRY R. GREENE.
